UNITED STATES PATENT OFFICE.

DE WITT C. HUNTLEY, JR., OF KANSAS CITY, KANSAS.

PENCIL.

No. 874,077.

Specification of Letters Patent.

Patented Dec. 17, 1907.

Application filed April 23, 1906. Serial No. 313,208.

To all whom it may concern:

Be it known that I, DE WITT C. HUNTLEY, Jr., citizen of the United States, residing at Kansas City, in the county of Wyandotte and State of Kansas, have invented certain new and useful Improvements in Pencils, of which the following is a specification:

This invention relates to improvements in pencils and the object of my improvements is to provide a pencil especially adapted for use by women who find it convenient to insert pencils in their hair when they are not in use.

In carrying out my invention I have combined with a pencil or pencil holder which may be of any convenient form or construction an extension in the form of a crook or loop, which in connection with the pencil or holder is adapted to be inserted in the hair and held against accidental displacement, and at the same time, may be readily removed for use.

In the accompanying drawing which forms a part of this application I have shown a preferred and a modified form of my invention in the following views:

Figure 1 is a side elevation of a pencil constructed according to my invention; Fig. 2 is a longitudinal section on an enlarged scale of the pencil portion of the invention; Fig. 3 is an elevation of a modification of the device shown in Fig. 1; Fig. 4 is a fragmentary longitudinal section on an enlarged scale of portions of the device shown in Fig. 3.

Referring to the drawings in detail, 5 represents the extension portion of my invention which is made of bone, celluloid, hard rubber or other suitable substance formed in the shape of a crook or loop having inwardly extending portions 6 and 7 and an outwardly tapering end 10. The end of the extension adjacent to the part 7 is inserted in a hollow pencil tube 8 of ordinary construction and is held rigidly therein by flanging the end of the tube as at 11 and causing said flanges to engage a corresponding annular recess or groove in the extension; as clearly shown in Fig. 2. The pencil is supplied with a lead 9

and may be of the design shown or any other suitable design or construction.

As shown in Fig. 3, the joint between the pencil 8 and the extension is covered by an elliptical rubber eraser 14, which has a double function in that it not only serves as an eraser but also coöperates with the portion 6 of the extension which it embraces, in holding the device in the hair.

As shown in Fig. 4 the inner end of the pencil holder 8, is formed with spiral threads 12, and the corresponding end of the extension is formed with external spiral threads 13 which are adapted to be screwed into the threads 12 of the holder and such joint is covered by the rubber 14. When made according to this modification if the pencil holder should become broken or worn out, a new one can be easily applied to the extension as will be apparent.

It is obvious that a pencil provided with the extension described can not only be disposed of in the manner stated but can be suspended on a hook or nail if desired. It is also obvious that instead of making the pencil holder hollow and the extension solid, I may reverse the construction without departure from the essential functions and principles of my invention. It is also plain that various methods may be utilized for joining a hair engaging extension with a pencil or pencil holder all within the scope of my invention.

Having thus described my invention what I claim, is:

1. A pencil consisting of a lead-holding member and a crook member connected therewith, the lead-holding member being substantially longer than the crook member, whereby its use will not be interfered with by the crook member.

2. A pencil consisting of a lead-holding member and a crook member detachably connected therewith, the lead-holding member being straight and substantially longer than the crook member.

3. A pencil consisting of a lead-holding member and a crook member connected

therewith, said crook member having portions approaching and receding from the pencil holding member, and means adapted to coöperate with the crook member to grip 5 the article to which the device may be attached.

4. A pencil or pencil holder consisting of a hollow metallic body, a lead secured therein, a crook extension having one end secured to

said body, and a rubber eraser secured at the 10 junction of said extension and pencil body for the purpose set forth.

In testimony whereof I affix my signature in presence of two witnesses.

DE WITT C. HUNTLEY, JR.
